APPARATUS FOR HANGING TOBACCO

Gorden Don Harris, Sound Beach, Conn., assignee to The Industrial Dryer Corporation, Stamford, Conn., a corporation of Connecticut

Application September 15, 1930, Serial No. 482,083

10 Claims. (Cl. 131—21)

This invention relates to the treatment of tobacco and more particularly has reference to methods and apparatus for suspending hands of tobacco, during treatment.

5 Heretofore in the treatment of tobacco with gases to dry or condition the same, the tobacco is generally placed in bundles which are known as hands. A plurality of hands of tobacco are arranged on that is termed "tobacco carrying sticks". These sticks are positioned within the treating chambers of the tobacco conditioning apparatus in any desired number. The treating apparatus in many instances is constructed so that a plurality of the tobacco carrying sticks are arranged therein either fixedly or detachably.

10 Hands of tobacco to be treated are held in the desired spaced relation by means of the tobacco carrying sticks. One method of positioning the hands of tobacco on the sticks comprises separating the leaves of tobacco constituting a hand into two equal portions and placing the hand over the stick so that the two equal portions of leaves straddle the stick. In this instance the stick may be made triangular so as to better fit 15 the hand of tobacco straddling the same.

20 Other developments have been made in which the hands of tobacco are attached to the tobacco carrying sticks by various devices. For instance, the hands of tobacco may be attached to sticks by 25 spring clips or other means for frictionally retaining the same in engagement with the sticks. In other instances, wire hooks are provided, adapted to pierce the stems of the tobacco so as to retain the same in engagement with the sticks. Still 30 other devices consist of prongs or wire attachments for passing between the leaves of tobacco so as to hold the same in proper relation to the tobacco carrying sticks.

35 While many developments have been made in the prior art to produce a variety of means for suspending the tobacco in the treating chamber, nevertheless, there is as yet no device which serves adequately to support and spread the leaves of tobacco so as to permit the most advantageous 40 access of the conditioning gas to all portions of the tobacco undergoing treatment.

45 The major object of this invention is to devise apparatus for hanging tobacco in a treating apparatus which avoids the disadvantages inherent in the prior art.

50 Another object of this invention is to provide apparatus for suspending tobacco in a treating chamber so as to permit the maximum degree of access of the conditioning gas to all portions of the tobacco undergoing treatment.

55 Still another object of this invention is to provide apparatus for hanging tobacco in a manner so as to support and spread the leaves thereof and yet engage the tobacco at only three lines of contact.

60 Yet another object of this invention is to provide an attachment for a tobacco carrying stick onto which hands of tobacco may be placed and removed in a most advantageous manner and which will support and spread the leaves of the 65 tobacco hand.

65 In accordance with the present invention, a plurality of devices are associated with the tobacco carrying stick by means of which, hands 70 of tobacco are supported by the stick. The devices may be formed from wire-like material or material in other forms and are preferably shaped so as to substantially produce a skeleton of a triangular prism. It has been found 75 advantageous in many instances to form the devices for supporting tobacco by the carrying sticks of a plurality of loops in the form of a UU. Each loop in the UU-loop is preferably arranged so that the plane in which one loop lies is at an 80 angle to that in which the other loop lies. When completed the UU-loop is in the form of a skeleton triangular prism and may be attached in any suitable manner to the tobacco carrying stick.

85 In order to make my invention more clearly understood, I have shown in the accompanying drawing, means for carrying the same into practical effect without limiting the improvements in their useful applications to the particular constructions which, for the purpose of explanation, 90 have been made the subject of illustration.

85 In the drawing:

Figure 1 is a perspective view of a tobacco carrying stick or lath on which is arranged a plurality of devices constructed in accordance with 95 the present invention.

Figure 2 is a side view of one of the devices shown in Figure 1 attached to the tobacco stick.

Figure 3 shows a device somewhat similar to that shown in Figure 1 modified as to the manner 100 of attaching the same to the tobacco carrying stick.

Figure 4 illustrates still another modification of the device for supporting tobacco by the stick.

Figure 5 shows a still further modified form 105 of the present invention in which the hands of the tobacco carrying device are formed so as to clasp the tobacco carrying stick or lath.

Figure 6 shows still another modified form of 110 the invention analogous to that shown in Fig-

ure 5 but formed in a somewhat different manner.

Figure 7 illustrates a form of the invention in which the free ends of the loops constitute the attachment and are formed so as to engage four sides of the square tobacco carrying stick.

Figure 8 is another modified form of the invention in which a tobacco attaching device extends from each side of the tobacco carrying stick 10 or lath.

Figure 9 is a view disclosing a still further modified form of the invention which illustrates the broad concept of carrying the same into effect.

As shown in the drawing the present invention comprises providing a plurality of attaching devices on a stick or lath of the type adapted to be positioned within the treating chamber of a tobacco conditioning device. As hereinbefore pointed out, the prior art devices did not serve to both support and spread the leaves of a hand of tobacco so as to permit the maximum access of the treating gas to all portions of the tobacco.

One of the most commonly employed devices for suspending tobacco in a treating chamber is the so-called triangular tobacco carrying stick or lath over which the hands of tobacco are straddled. This type of tobacco stick or lath is disadvantageous in that a large portion of the tobacco leaves are in engagement with the surfaces of the stick or lath and thereby could not receive access to the conditioning gas. Necessarily this lack of access to the conditioning gas would cause non-uniform conditioning of the leaves of tobacco, and thereby cause a waste and the production of inferior tobacco. This feature is particularly disadvantageous in the case of preparation of leaves of tobacco for cigar wrappers in which instance leaves of highest quality are required.

The present invention overcomes the prior art disadvantages by providing a skeleton-like triangular-prism attachment for the tobacco carrying stick over which the hands of tobacco may be placed. As shown in the several figures of the drawing, a plurality of the skeleton-like triangular prisms indicated generally by reference numeral 1 are arranged on a tobacco carrying stick 2.

The attachments 1 may consist of a plurality of U-loops 3 and 4 which have their free ends secured to a sleeve 5 adapted to be snugly received on the tobacco carrying stick or lath 2. The U-loops are arranged so as to project horizontally from the tobacco carrying stick and are also positioned so that the legs 6 and 7 of the loops 3 and 4 respectively lie in juxtaposition and so that the legs 8 and 9 of the loops 3 and 4 respectively are spaced apart a distance approximating the width of the loops. This construction when completed gives the appearance of a skeleton of a triangular prism, the two legs 6 and 7 of the loops 3 and 4 being so closely arranged as to give the appearance of one of each of the triangular prisms and the legs 8 and 9 serving as the other two edges of the triangular prism. The free ends of the loops may be attached to the sleeves 5 in any desired manner and the sleeves 5 may be secured to the tobacco carrying stick 2 or lath by any means, for instance, such as the nails 10 shown in Figures 1 and 2.

When assembled on the tobacco carrying stick the devices 1 are spaced apart a distance depending upon the size of the tobacco hands being treated. After the attachments 1 are properly

spaced on the tobacco carrying sticks, the hands of tobacco may be placed over the attachments, as is clearly shown in Figure 1. When a hand of tobacco is positioned over the attachment, the apex of the skeleton triangular prism formed by the legs 6 and 7 of the loops 3 and 4 serves as a means for supporting the hand of tobacco and the legs 8 and 9 of the loops 3 and 4 respectively serve as means for spreading the leaves apart so as to permit the access of the conditioning gas thereto.

It will be obvious that when the hand of tobacco is supported by the attachments 1, that there will be substantially only three lines of contact between the tobacco leaves and the attachments 1. One of these will be up near the stem or butt portion of the leaves, which is immaterial, and the other two will be at a somewhat lower point of the leaves as shown in Figure 1.

It will be appreciated that this device is a material improvement over the heretofore employed triangular sticks or laths which prevent access of the conditioning gas to a relatively large surface of the tobacco leaves.

While the devices shown in Figures 1 and 2 have been described as being formed of a pair of U-loops, I wish it to be clearly understood that both loops can be formed of a single piece of wire, for instance, a piece of wire bent to form a UU. After forming the UU, the loops of the UU may be bent relatively to each other to form a skeleton of a triangular prism as hereinbefore mentioned.

In order to illustrate the susceptibility of the present invention to modification, I have shown in the several figures of the drawing many and varied modifications of means for attaching the devices to the tobacco carrying stick or lath. In Figure 3, for instance, the free ends of the UU-loop are shaped so as to provide eyelets 11 through which attaching elements 12 may be passed to secure the skeleton-like triangular prism to the tobacco carrying stick 2. This form may prove advantageous in certain instances when it is undesirable to employ the sleeves 5, hereinbefore described.

If found desirable, the present invention may also be modified so as not to require the use of any attaching means. In Figure 4, for instance, the central leg of the UU indicated by the reference numerals 6 and 7, has its free end bent downwardly as at 13, so as to clasp the tobacco carrying stick 2. The free ends of the legs 8 and 9 of the UU-loop are bent upwardly as at 4 so as to more securely attach the device 1 to the tobacco carrying stick. If desired, this form of the invention may be further modified by providing sockets or recesses in the tobacco carrying stick 2 into which the free ends of the legs of the UU-loop may be inserted. This latter form of the invention has not been illustrated, but it is believed that with the showing in Figure 4 and the disclosure herein, that it may be readily understood.

Another form of the present invention is shown in Figure 5, in which the free end of the central leg of the UU-loop is bent downwardly at 15, then horizontally at 16, upwardly at 17, and horizontally in the opposite direction at 18. By so shaping the free end of the central leg of the UU-loop, engagement is effected between the ends of the loop and all four sides of the tobacco carrying stick 2. This gives a rather tight fitting engagement between the attachment 1 and the tobacco carrying stick. The outside legs of

the loop 8 and 9 have their free ends bent upwardly at 19, horizontally at 20, and downwardly at 21, so that three sides of the tobacco carrying stick are engaged. With the arrangement just described, the attachment is securely fixed to the tobacco carrying stick and may not be accidentally displaced.

In Figure 6 there is shown another modification of the means of attaching the device 1 to the tobacco carrying stick. This form consists of a structure in which the central legs of the UU-loop 6 and 7 are bent downwardly at 22 and horizontally at 23 to effect a two-surface engagement between the tobacco carrying stick and the central leg of the UU-loop. The legs 8 and 9 of the loop are constructed similarly to the form shown in Figure 5 and are indicated by similar reference numerals primed.

A still further modification of the invention is shown in Figure 7 in which the central leg of the loop is bent back upon itself at 24, then downwardly at 25, horizontally in the opposite direction at 26, and then upwardly at 27. By so forming the free end of the central leg of the UU-loop a somewhat stronger construction is afforded than in the foregoing illustrations. The outside legs of the loop are formed somewhat similarly to those shown in Figures 5 and 6 but consist of additional extensions 28 adapted to engage the bottom surface of the tobacco carrying stick 2.

The construction just described, it will be appreciated, contains sufficient bends so as to provide enough engaging surfaces between the device 1 and the tobacco carrying stick 2 to permit the device to carry relatively heavy hands of tobacco without placing much strain on the joint between the device and the tobacco carrying stick.

In order to illustrate the broadest concept of the present invention, I have shown in Figure 9 a construction which consists of three members arranged in the form of a skeleton of a triangular prism, adapted to support a hand of tobacco. This construction consists of a plurality of members 29, 30, 31 of any desired form, attached to a sleeve 5, adapted to be fitted on a tobacco carrying stick 2. The member 29 serves as the support for the hand of tobacco and if desired, may be constructed more heavily than the members 30 and 31, which serve merely to spread the leaves of tobacco a sufficient distance to permit access of the gas thereto.

While this form of the invention has been described as consisting of a plurality of members attached to sleeve 5, I wish it to be clearly understood that the members 29, 30, 31 may be inserted directly in the tobacco carrying stick 2, in which instance sleeve 5 will not be necessary. Also the free ends of the members 29, 30, 31 may be rounded in any desired manner so as to avoid any tearing of the tobacco leaves, while placing the hands of the tobacco on the attachment or removing the same therefrom. One manner of preventing tearing of the tobacco leaves is to bend the free ends of the members 29, 30, 31 inwardly, as shown in Figure 9. If desired, the inwardly bent ends of the members 29, 30, 31, may be connected by soldering, welding or any other manner so as to absolutely avoid any sharp edges which may tear the tobacco leaves.

While in the foregoing description the attachments 1 have been described as extending from only one side of the tobacco carrying stick, I wish it to be understood that the attachments 1 may be extended from both sides of the tobacco

carrying stick as shown in Figure 8. For the purpose of illustration, the form of invention which consists of the sleeve 5, has been shown in the figure, but it should be clearly understood that any of the other forms shown may be modified so as to extend from both sides of the tobacco carrying stick.

Devices constructed in accordance with the present invention are of particular advantage in the tobacco industry in that hands of tobacco may be supported thereby in a manner so as to permit the maximum access of the conditioning gas to all portions of the tobacco leaves. The invention herein described is also of advantage in that a plurality of the devices disclosed may be arranged on the so-called tobacco carrying sticks or laths and the hands of tobacco placed thereon without any danger of tearing or otherwise damaging tobacco leaves. When it is desired to unload the treating chamber of the tobacco conditioning apparatus, it is merely necessary to remove the sticks or laths 2 from their supports, and tilt the same so as to permit the hands of tobacco to slide off into a suitable receptacle. In the form of invention showing the attachments extending from both sides of the tobacco carrying stick, it will merely be necessary to tilt the stick first in one direction and then in the other to remove tobacco hands from both sides of the attachments.

I have found by actual experience that it is advisable to construct the attachments herein disclosed of material not susceptible to corrosion. Corrosion would cause the accumulation of incrustations on the metal and would probably damage the tobacco leaves. For instance, when constructing the device of copper wire, it is desirable to tin or otherwise plate the wire so as to avoid corrosion. Of course, suitable alloys resistant to corrosion, such as occurs in tobacco treating apparatus, may also be employed as material for constructing the devices disclosed.

I claim:

1. A tobacco hanger comprising a stick and means carried by the stick for supporting and spreading the leaves of a hand of tobacco, said means comprising a pair of U-shaped loops secured to and extending from the side of the stick, and arranged to support and spread the tobacco by three-point engagement therewith.

2. A tobacco hanger comprising a stick and means secured to the stick for supporting and spreading the leaves of a hand of tobacco, said means comprising a pair of U-shaped loops extending from the side of the stick, one leg of one loop being positioned in juxtaposition to one leg of the other loop and the other legs being spaced apart.

3. A tobacco hanger comprising a stick, means secured to and extending from the side of the stick adjacent the top thereof to support a hand of tobacco and means secured to and extending from the stick adjacent the lower portion thereof for spreading the leaves of the hand.

4. A tobacco hanger comprising a tobacco carrying stick, means for supporting tobacco thereby, said means consisting of a sleeve adapted to snugly engage the stick and a pair of U-shaped loops, the open ends of which are secured to said sleeve.

5. A tobacco hanger comprising a tobacco carrying stick, means for supporting tobacco thereby, said means consisting of a sleeve adapted to snugly engage the stick and a double U-shaped loop assembly, one loop lying in a plane at an

angle to that in which the other loop lies, the open ends of the loops being secured to the sleeve.

6. A device for hanging tobacco on a tobacco carrying stick comprising a wire like member having the form of a UU loop, the U portions of said loop being positioned in angular relationship to each other so that the legs thereof form a skeleton of a triangular prism, and means for attaching the loop to the carrying stick.

10. 7. A device for hanging tobacco on a tobacco carrying stick comprising a wire like member having the form of a UU loop, the U portions of said loop being positioned in angular relationship to each other so that the legs thereof form a skeleton of a triangular prism, and means for attaching the loop to the carrying stick.

15. 8. A device for hanging tobacco on a tobacco carrying stick comprising a wire like member having the form of a UU loop, the U portions of said loop being positioned in angular relationship to each other so that the legs thereof form a skeleton of a triangular prism, a holding member mounted on said stick, and a sleeve adapted to be non-rotatably mounted on the tobacco carrying stick by being joined to said holding means, the open ends of said loops being attached thereto.

20. 9. A device for hanging tobacco on a tobacco carrying stick comprising a wire like member having the form of a UU loop, the U portions of said loop being positioned in angular relationship to each other so that the legs thereof form a skeleton of a triangular prism, a holding member mounted on said stick, and a sleeve adapted to be non-rotatably mounted on the tobacco carrying stick by being joined to said holding means, the open ends of said loops being attached thereto.

5. skeleton of a triangular prism, the ends of said loops having eyelets formed therein for attaching the device to the tobacco carrying stick.

9. A tobacco hanging device comprising a tobacco carrying stick, means for supporting tobacco thereby, said means consisting of a sleeve adapted to snugly engage the stick, a pair of U-shaped loops, one loop being positioned in a plane at an angle to that in which the other loop lies, the open ends of which are secured to said sleeve so as to extend from one side thereof, and a plurality of similar loops extending from the other side of said sleeve.

10. A tobacco hanging structure comprising a tobacco carrying stick, a skeleton like triangular prism of bent wires with substantially parallel portions secured to and extending horizontally from one side of the stick and a similar skeleton like triangular prism secured to and extending from the other side of said stick, each of said skeleton like prisms being adapted to support and spread a hand of tobacco and engage the same only at three lines of contact.
